UNITED STATES PATENT OFFICE.

ELON A. MARSH, OF DETROIT, MICHIGAN.

SUPPLY-VALVE.

SPECIFICATION forming part of Letters Patent No. 723,698, dated March 24, 1903.

Application filed August 13, 1902. Serial No. 119,483. (No model.)

To all whom it may concern:

Be it known that I, ELON A. MARSH, a citizen of the United States, residing at Detroit, county of Wayne, State of Michigan, have invented a certain new and useful Improvement in Supply-Valves; and I declare the following to be a full, clear, and exact description of the invention, such as will enable others skilled in the art to which it pertains to make and use the same, reference being had to the accompanying drawings, which form a part of this specification.

This invention relates to supply-valves for filling tanks or cisterns; and it has for its object a simple automatically-acting valve that will control with practical accuracy the quantity of water passing through it in a given time irrespective of the pressure on the supply side—that is, practically the same amount of water will be delivered in a unit of time whether the pressure be high or low. I do not mean to say that the amount will be accurately measured, but that the deviation from a stated amount will be so small as to be practically unimportant.

In the drawings, Figure 1 is a vertical section of the valve and the attached float. Fig. 2 is a detail of the piston-cylinder employed. Fig. 3 is a detail of the piston-valve employed. Fig. 4 is a plan view of the top end of the valve and casing.

2 indicates the water-inlet pipe, which is to be connected to any suitable source of supply for water.

3 is the passage leading directly to the nozzle or valve orifice a.

The end of the pipe 2 is contracted, and on the external surface of the pipe, near the end, is seated a plate or spider 4 on the shoulder A of the pipe. The part of the pipe which is immediately next to the end of the nozzle is externally cylindrical throughout that part of it over which the piston-disk C (hereinafter spoken of) reciprocates. The range of such reciprocation is short.

B indicates a cylinder that rests on the plate 4 and is secured thereto by any suitable means—as, for example, by a screw d. The top of the cylinder B is closed in except for a central opening through which engages the stem U of a valve D. Provision is made for the escape of water from the cylinder B,

and the escape-passages are located below the piston-disk C, and, as shown in the drawings, the passages lead through the side walls 55 of the cylinder. The end of the pipe is arranged as a valve-seat, and a flat valve D rests on this valve-seat. The stem U of the valve D extends through a central aperture in the cover-plate or end plate of the cylinder B, and from the stem U extend arms C', that support at their outer extremities a piston-disk C, that is bored centrally to engage over the cylindrical part of the nozzle end of the pipe 2, and the piston-valve engages 65 loosely in the cylinder B—that is, there is or may be some freedom for the escape of water around the periphery of the piston-disk or between the pipe and the edges of the hole. Provision is to be made for the escape 70 of water either at these places or by means of holes through the disk, and the provision for the escape of water is to be made with reference to the amount of water that is required for a given period of time. 75

The upper end of the valve-stem U is suitably connected to a float-lever E, that supports a float F. This connection may be in any one of various ways. As shown in the drawings, the rock-arm e engages in a notch 80 in the stem U. The rock-arm is pivoted on brackets D', that rise from the cylinder B, and opposite the rock-arm e is the float-arm, which supports the float F. The leverage is arranged to lift the valve from its seat when the 85 float ceases to be supported by water and becomes a weight and to close the valve on its seat when the water in the tank lifts the float.

In action the pressure of the water in the pipe 2 tends to push the valve from its seat, 90 and the weight of the float tends to lift the valve from its seat. The two coact. As soon as the valve rises from its seat water enters the chamber in the cylinder B, and the pressure acting on the piston C tends to close the 95 valve toward its seat; but as the orifice closes the water entering the piston-chamber is reduced in quantity and the closing pressure that acts on the piston C is reduced and the action and reaction produces an equilibrium 100 whose determinant factors are the capacity for escape of water past the piston C and the valve, and these having been regulated for a definite passage of water the amount deliv-

ered corresponds closely thereto irrespective of the pressure in the pipe 2. There is always a high pressure in the pipe 2, a reduced pressure in the cylinder B, and either no pressure at all or a low pressure outside the cylinder B—no pressure at all when there is a free escape for all the water that emerges and low pressure when the structure is so located in the tank that there is water surrounding the cylinder. The chamber within the cylinder becomes thus one of intermediate pressure between the high pressure in the pipe 2 and the low pressure that is outside the structure.

15 What I claim is—

1. In a pressure-reducing supply-valve, a cylinder containing an intermediate-pressure chamber, a passage arranged to deliver water into said chamber, a piston arranged to be actuated by water in the intermediate-pressure chamber, a valve connected with said piston arranged to regulate the inflow into said chamber, the valve and the piston being arranged to be oppositely actuated, the valve

25 by high pressure, and the piston by intermediate pressure, substantially as described.

2. In a pressure-reducing supply-valve, a valve arranged to open by force of the supply-pressure and by a weight-and-lever mechanism, and to close by a float-and-lever mechanism, a piston connected to said valve, a chamber for said piston, the said chamber being provided with means for the free egress of water therefrom, on that side of the piston 35 which is opposite the valve connected therewith, a valve-controlled orifice arranged to deliver water into the piston-chamber, a restricted outlet-passage from the chamber of substantially unvarying capacity, substantially as described.

40 3. In a pressure-reducing supply-valve, the combination of a casing provided with a chamber, an orifice arranged to deliver a supply of

water to the said chamber, an orifice of substantially unvarying capacity to deliver water 45 from said chamber, a valve arranged to regulate the capacity of the inlet-orifice, and means actuated by the pressure in said chamber for actuating said valve, substantially as described. 50

4. In a pressure-reducing supply-valve, the combination of a chamber arranged to contain water at high pressure, a chamber arranged to contain water at lower pressure, a communicating passage between the two 55 chambers, a passage leading out from the second chamber and arranged for a substantially unvarying capacity, a piston arranged to be actuated by pressure of water in the second chamber, a valve connected to said 60 piston and arranged to regulate the orificial capacity of the passage between the two chambers, the piston and the valve being arranged to assume a balanced condition as against the pressures of the water in the high-pressure 65 chamber against the valve, and the water in the piston-chamber against the piston, substantially as described.

5. In a pressure-reducing valve, the combination of a valve and a piston connected therewith arranged to reciprocate in a chamber closed at one end and open at the opposite end, the peripheral walls and the closed head of the chamber constituting part of the casing and having opposed thereto the piston 75 and a supply-orifice, a restricted outlet-passage from the chamber and a float and suitable connections therewith, substantially as described.

In testimony whereof I sign this specification in the presence of two witnesses.

ELON A. MARSH.
